PUMP INSTALLATION

Earl R. Ortman, Milwaukee, Wis.

Application April 24, 1953, Serial No. 350,949

4 Claims. (Cl. 166—75)

This invention appertains to wells and well pumps and more particularly to well installations of the so-called pitless type, embodying a submersible pump.

According to various state codes, the well casing must be sealed against the entrance of foreign matter and drainage water and yet, from time to time the submersible pump and its motor must be removed and inspected for repairs. Heretofore, this has necessitated the digging down around the well casing and removing a section thereof and then uncoupling of the flow pipe and supply pipe from the well.

It is one of the primary objects of my invention to provide a novel and safe well installation of the pitless and submersible pump type, and in which the pump and its motor can be conveniently and quickly pulled out for repairs and inspection by the mere removal of the sealing cap of the well casing and without the necessity of digging around the casing, removing sections thereof, etc.

Another salient object of my invention is to provide the well casing below the frost line with a laterally or radially extending sealed box forming a part of the casing and communicating with the interior thereof carrying, as a sealed part, a pipe joint for connection with the supply pipe for water leading to the place of water use and a coupling on the well flow pipe having a slip connection with the pipe joint carried by the box, whereby to pull the flow pipe and the pump and its motor it is merely necessary to pull up on the flow pipe to disengage the slip joint parts, and to shift the flow pipe laterally in the casing to move the coupling out of the box and then pull up on the flow pipe and the parts carried thereby.

With these and other objects in view, the invention consists in the novel construction, arrangement and formation of parts as will be hereinafter more specifically described and claimed, and illustrated in the accompanying drawing, in which drawing,

Figure 1 is a vertical sectional view through the upper part of a well installation of the pitless and submersible pump type embodying my invention.

Figure 2 is a view similar to Figure 1, but showing the sealing cap removed from the top of the well casing and the flow pipe partly raised to disengage the slip joint parts and laterally shift them to permit the pulling of the well pipe and the pump and its motor.

Figure 3 is a horizontal sectional view taken on the line 3—3 of Figure 1 looking in the direction of the arrows illustrating the arrangement and the connection of the box with the well casing.

Figure 4 is an enlarged fragmentary detail vertical sectional view taken on the line 4—4 of Figure 3, looking in the direction of the arrows, illustrating the novel connection between the coupling carried by the flow pipe and the joint carried by the box.

Referring to the drawing in detail, wherein similar reference characters designate corresponding parts throughout the several views, the letter W indicates a well installation embodying one of the preferred forms of my invention.

As illustrated, the well installation includes a well casing 5 embodying a plurality of casing sections 6. The casing 5 protrudes above the ground a predetermined distance according to a particular state code for wells, and the upper end of the casing 5 is closed and sealed by a removable cap 7. The cap 7 has attached thereto a flow pipe 8 leading from the pump. The pump and its motor are of a type now found in the open market

and have not been shown. Also connected with the cap 7 is a conduit for the electric cable 9, leading to the pump motor and an air vent 7'. All of the parts just mentioned are standard equipment, and now available to well users.

In accordance with my invention, I provide a section 6 of the casing 5 below the frost level with a laterally extending box or casing 10, and the well casing section is cut away as at 11, so that the box or housing 10 has communication with the interior of the well casing. In order to form a tight leak-proof joint, between the well casing and the box or housing 10, the edge of the box or housing is securely welded, as at 12, to the well casing. Secured to the outer wall of the box or housing 10, adjacent to its lower end is an angle pipe joint 13, and this joint is welded, as at 14, to this wall of the box or housing, so that a fluid tight connection will be had between the joint and the box. Hence, leakage of water around the joint 13 into the box is eliminated. The joint 13 permits connection of the water supply pipe 14 with the box.

Intermediate the length of the flow pipe 8, I incorporate a T-coupling 15 and the laterally extending arm of this coupling 15 has connected therewith an elbow fitting 16. The elbow fitting and the elbow joint 13 carry respectively sections 17 and 18 of a well known type of slip joint 19, and the sections 17 of the slip joint 19 can be readily moved on or removed from the section 18 of the slip joint. The T-coupling 15 above its laterally extending arm is closed by a plug 20 so that flow of water will be from the pump through the lower part of the flow pipe 8, and thence into the water supply pipe 14.

In use of my invention and after the well casing 5 is sunk in the ground in the usual manner with the box 10 and elbow 13 welded thereto, the supply pipe 14 is connected to the elbow 13 and is led to the desired point; the casing 5 is now ready to receive the pump and its motor. The parts 15, 16 and 17 are connected to the flow pipe 8 and the pump and its motor and the flow pipe are lowered into the casing. Upon the reaching laterally to move the section 17 of the slip joint into the box 10, after which the flow pipe is further lowered so that the section 17 will engage over and receive the section 18. In this way, the weight of the pump and the flow pipe is partly supported by the elbow joint 13. Upon proper installation of the pump in the well, the casing is sealed by the cap 7 and the well is ready for use. The direction of the flow of water is indicated by arrows in Figures 1 and 4.

It is to be understood, that in the installation of the well casing, a shallow pit (not shown) is dug around the well hole to permit the placing of the casing 6 with the housing 10 in the ground. This pit communicates with a trench (not shown) provided for the pipe 14 and after installation of the well casing and the pipe 14, the pit and trench are then filled with earth.

When it is desired to remove the pump and its motor for repairs or inspection, it is merely necessary to remove the cap 7 and pull up and shift the flow pipe 8, as is clearly shown in Figure 2, of the drawing, after which the flow pipe and the pump and its motor can be easily pulled from the well casing.

It can be seen that with the use of my invention, all digging around the well casing and the removal of parts of the well casing, is eliminated.

Changes in details may be made, without departing from the spirit or the scope of this invention, but what I claim as new is:

1. In a well of the pitless submersible type, a well casing including a plurality of sections, one of the sections having an opening in its wall, a laterally extending housing rigidly secured around the opening to the well casing section in fluid tight engagement therewith, an elbow joint rigidly secured to the housing and having water tight connection therewith and adapted to have a water supply pipe connected therewith, a flow pipe, a T-coupling incorporated in the length of the flow pipe, and a slip joint including a section connected with one arm of the T-coupling and another section connected with the elbow joint, whereby the flow pipe can be con-

3

nected with the elbow joint and whereby the flow pipe can be disconnected from the elbow joint and shifted laterally away from the housing.

2. In a well, a well casing, an elbow joint rigidly secured to the well casing and in water tight connection therewith, a supply pipe leading from the well connected to one end of the elbow joint, a flow pipe extending longitudinally of the casing, a T-coupling interposed in the length of the flow pipe, and a slip joint having one section connected with the T-coupling and another section carried by the elbow joint whereby the flow pipe and the elbow joint can be inter-connected by moving one section of the joint over the other.

3. In a well, as defined in claim 1, a sealing plug closing the flow pipe above the slip joint section carried by the T-coupling.

4. As a new article of manufacture a well casing section having a longitudinally extending opening therein, an outwardly projecting housing surrounding the opening and having water tight connection with the casing around the opening, and an elbow joint positioned in the lower end of the housing and rigidly secured to the housing in water tight connection therewith, said elbow joint being disposed wholly within the housing, leaving said casing unobstructed.
